United States Patent

Des. 235,344
Patented June 10, 1975

235,344

LAVATORY

Stanley F. Korol, 457 Shepard Road,
Mansfield, Ohio 44907

Filed Dec. 28, 1973, Ser. No. 429,320

Term of patent 14 years

Int. Cl. D23—01

U.S. Cl. D23—58

FIG. 1 is a perspective view taken from the top and front of a lavatory showing my new design;

FIG. 2 is a perspective view taken from the top and rear thereof;

FIG. 3 is a front elevational view thereof;

FIG. 4 is a side elevational view thereof;

FIG. 5 is a top plan view thereof; and

FIG. 6 is a sectional view taken on line 6—6 of FIG. 5.

I claim:

The ornamental design for a lavatory, as shown.
